RAIL END CONNECTER

Cliff Edwards, Beverly Hills, Calif.

Application June 12, 1933, Serial No. 675,399
Renewed April 21, 1936

5 Claims. (Cl. 238—195)

This invention relates to a rail connector. Rail connections are usually effected by means of fish plates which are attached by bolts passing through holes in the webs of the abutting rail ends. This necessitates making similar holes in the fish plates for the bolts. In that kind of a connection, if it happens that the abutting ends of the rail are not located over a cross tie, there is no substantial support immediately under the rail end. Even if the two rail ends do abut over a cross tie, by reason of the fact that the cross tie is somewhat compressible, the rail end from which the wheel passes tends to become depressed, thereby causing more or less of a shock to the wheel as it passes from this rail end to the next. This causes a recurrent noise that is always unpleasant to passengers during the day, and is positively annoying to passengers occupying berths in sleeping cars.

One of the objects of my invention is to overcome this objection and to provide a connection for the abutting rail ends which will enable the wheels of the train to pass from one rail to the next noiselessly, and without any jar or shock, and to connect the rail ends together in such a way that the rail will react to the wheel as though it were substantially one continuous rail.

A fish plate connection between rail ends does not reinforce the rails to any considerable extent as regards the possibility of the rails spreading, and many accidents have happened heretofore on account of such spreading of rails particularly on curves where the centrifugal force acting on the train subjects the outside rail to a considerable stress in a horizontal plane.

Another object of this invention is to provide a rail end connector of simple construction, which will overcome the objections referred to above, and which will provide a substantial support for the abutting rail ends, thereby preventing a shock or hammer blow as the wheel rolls from one rail end to the next.

A further object of the invention is to provide a rail end connector that will avoid the necessity for the use of fish plates and bolts through the webs of the rails.

A further object of the invention is to provide a construction which will enable a connection to be made between the rail and cross ties which will tend to prevent spreading of the rails.

The joints where rails abut may, of course, occur directly over a cross tie or they may occur between cross ties. One of the objects of this invention is to provide a connector which is

adapted to be used in either of these situations, in one case operating as a bridge between the two adjacent ties and in the other case operating as a seat for the rail on the tie above which the rails abut.

A further object of the invention is to provide a construction for rail connector which will enable the abutting rails to be securely braced in position, but which will allow for contraction and expansion of the rails due to changes of temperature; also to provide a construction whereby wedges may be employed for securing the rail connector to the rails, and to provide a construction involving the use of compressible means cooperating with the wedges to facilitate their being driven into position and to provide a constant resistance to the outward movement of the wedges.

Further objects of the invention will appear hereinafter.

The invention consists in the novel parts and combination of parts to be described hereinafter, all of which contribute to produce an efficient rail end connector.

A preferred embodiment of the invention is described in the following specification, while the broad scope of the invention is pointed out in the appended claims.

In the drawing:

Figure 1 is a plan upon reduced scale of a short portion of railroad track and illustrating two rail end connectors embodying my invention and incorporated into the railway construction;

Figure 2 is a vertical section upon a large scale taken about on the line 2—2 of Figure 1 and further illustrating details of the construction, the lower and outer portions of the cross ties being broken away; and

Figure 3 is a cross section taken about on the line 3—3 of Figure 2, the lower portion of the cross tie being broken away.

Referring more particularly to the parts, 1 indicates a short section of railway track in which rails 2 are laid upon cross ties 3, and in this view 4 and 5 indicate two rail end connectors embodying my invention. The connector 4 is indicated as bridging two adjacent ties indicated specifically by the numerals 3a and 3b, while the connector 5 is illustrated as seated entirely on a single cross tie indicated by the numeral 3c.

Referring more particularly to Figures 2 and 3, the connector comprises an elongated body member 6 which has a base 7 in the form of a plate to rest upon a cross tie 3a and this body member includes an upward extension 8, which

is of massive form so as to have considerable strength under compression. This extension 8 is integrally connected to the base 7 and between the base and the inclined under face 9 of the 5 upward extension 8 a socket 10 is formed. This socket is adapted to receive the adjacent rail flange 11 when the body member 6 is applied to the inner side of the rail. The face 9, as viewed in cross section in Figure 3, is substantially parallel to the upper inclined face 12 of the rail flange 11 and is disposed at a slight distance from the same so as to be capable of receiving a clamping wedge 13 that is driven into position from the end of the connector. The face 9 15 should also have a slight inclination in a longitudinal direction to correspond with the inclination or taper of the wedge, such as the wedge 14, indicated in Figure 2. The upward extension 8 is preferably of hollow, block form as shown, that 20 is to say, it has a cored opening 15 extending from end to end through it. The upper face of the extension or block 8 is formed with a shallow groove or channel 16 to provide clearance for the flanges of the wheels that roll on the track. 25

In order to give the connector considerable strength, it is provided with a relatively deep wall 17 which connects one edge of the base 7 with the outer side of the block or extension 8. Furthermore, I prefer to construct this part of 30 the connector so that the outer face 17a of the block or extension 8 constitutes a continuation of the adjacent edge of the base 7, and this face intersects with the upper inclined face 18 of the connector so as to produce a relatively high shoulder 19. This gives the block or upward extension 35 8 a considerable horizontal dimension and vertical depth.

The upper side of the block or extension 8 is formed with an inclined or beveled face 20 that 40 seats against the inclined under face 21 of the rail head 22. When the wedge 13 is tightened up, the face 20 is jammed against the under side of the head.

The connector also includes a clamping member 45 or clamping block 23 which has a cross section somewhat similar to that of the upward extension or block 8, that is to say, it has a beveled upper face 24 adapted to be jammed by the wedge 14 against the inclined under face 25 of the rail head on the outer side of the rail.

The clamping member 23 preferably includes an outwardly projecting flange 26 which is cast integral with it, and the outer edge of this flange and the outer edge of the base 7 are provided 55 with registering sockets 27 for receiving rail spikes such as the spikes 28 which are driven down into the cross ties.

In addition to this, I prefer to secure the clamping block 23 to the base by means of bolts 50 29 shoved up from below and tightened up by nuts 30 carried on the upper threaded ends of the bolts. The clamping member 23 is also preferably provided with a cored opening 31. These cored openings 55 15 and 31 considerably reduce the weight of material but are employed in making the connector without substantially reducing its strength. The presence of these cored openings 15 and 31 also facilitates the running of copper wire connections when it is necessary to provide a good 60 electrical connection between the rail ends.

Each connector is preferably provided with two spike sockets 27 which are located near the ends and also an intermediate socket 32. This enables the connector to be used as a bridge across two 75 adjacent cross ties as indicated in Figure 2 or,

by using the middle spike socket 32, the connector can be seated directly over a single cross tie as indicated at 5 in Figure 1.

If desired, the base 7 may be laid directly upon the upper face 33 of the cross tie but I prefer to counter-sink it into the cross tie, and for this purpose I provide the cross tie with a deep notch 34 (see Figure 3). In this way, a vertical shoulder 35 is formed in the cross tie, against which the outer edge of the connector abuts. This gives 10 a secure connection between the connector and the cross ties and tends to prevent the connector from shifting on the cross tie.

After the wedges 13 and 14 have been driven into place, their small ends are bent upwardly as 15 indicated at 14a in Figure 2. This upwardly bent toe 14a tends to prevent the wedges from working loose. The wedges also tend to remain tight by reason of the fact that I provide a pad or mat 36 under the bottom face of the rail and this pad 20 is preferably received in a recess 37 formed in the upper face of the base 7. This pad or mat may be made of highly compressed fiber or similar material which will be slightly compressed by the driving of wedges into position. It should be 25 noted, however, that when the wedges are tightened up, the rail is supported by the seats 20 and 24 under its head 22. Hence, when a heavily loaded wheel rolls from one rail to the next, there 30 can be no imperfect alignment between the upper faces of the two abutting rail ends.

It will be noted that in the connector 4 the notches 34 do not extend all the way across the cross ties but simply extend into the same from one side but when the connector is seated entirely 35 on a single cross tie, such as indicated at 5 in Figure 1, the notch 38 for the connector extends all the way across the upper face of the tie.

It will be noted that this connector can be 40 readily substituted for fish plates now in use for connecting rails already laid in tracks. The fish plates can be melted with other iron to cast the connectors embodying my improvements.

The use of the connector saves wear and tear 45 on the car wheels and prolongs the life of the rails by reducing the pounding effect which now occurs when the heavily loaded wheel passes from one rail to the next.

If car wheels are composed of compressed paper or rubber or other material, this connector will 50 serve the same purpose of saving wear and tear on such wheels.

It will be noted that the base of my connector has considerable area and, if desired, it can be seated directly on ballast driven under it like the 55 practice of driving ballast under cross ties. If this is done, the use of the connector will save a considerable length in cross ties as short cross ties can be used at such points.

It will be evident that my rail connector will 60 facilitate the electric bonding of the ends of the rails together, where this is necessary to increase the conducting efficiency of the rails on electric railways. In making such a bond, it is obvious that a flat copper strip can be laid between the 65 abutting faces 20 and 21, or 24 and 25 of Fig. 3. When the connector is clamped up, it is evident that such copper strips would be very tightly clamped against the rail ends.

It is understood that the embodiment of the 70 invention described herein is only one of the many embodiments this invention may take, and I do not wish to be limited in the practice of the invention, nor in the claims, to the particular embodiment set forth.

One of the advantages of my improvement is that the rail ends are held rigidly together without using through bolts passing through their webs. This avoids the necessity for drilling the 5 rail ends, and a considerable economy results from this fact.

What I claim is:—

1. In a rail connector, the combination of an elongated body member having a base to lie upon 10 the cross ties and having an upward extension of elongated form, with a socket to receive the rail flange between the base and said upward extension, said upward extension having a seat face abutting against the under face of the rail head, a clamping member of elongated form 15 opposite to said upward extension, means for bolting the same to the base, said clamping member having an upper face to seat against the lower face of the head, said socket 20 having an inclined face adjacent to the upper face of the rail flange and said clamping member having an inclined face adjacent to the rail flange on the other side of the rail, and wedges between the rail flange and said inclined faces 25 for clamping the upper faces of the body and the clamping member up against the under faces of the rail head, said wedges, said body and said clamping member being the sole means for securing the rail ends together.

2. In a rail connector, the combination of an elongated body member having a base to lie upon the cross ties and having an upward extension of elongated form, with a socket to receive the rail flange between the base and said upward extension, said upward extension being imperforated for bolts through the rail ends and having a seat face abutting against the under face of the rail head, a clamping member of elongated form opposite to said upward extension, means for bolting the same to the base, said clamping member being imperforated for bolts through the rail ends having an upper face to seat against the lower face of the head, said socket having an inclined face adjacent to the upper 45 face of the rail flange and said clamping member having an inclined face adjacent to the rail flange on the other side of the rail, and wedges between the rail flange and said inclined faces for clamping the upper faces of the body member and the clamping member up against the under faces of the rail head, said wedges, said body and said clamping member being the sole means for securing the rail ends together, said body member and said clamping member having 50 aligning notches on their edges to receive spikes.

3. In a rail connector, the combination of an elongated body member having a base to lie upon the cross ties and having an upward extension of elongated form, with a socket to receive the 60 rail flange between the base and said upward extension, said upward extension being imperforated for bolts through the rail ends and having a seat face abutting against the under face of the rail head, a clamping member of elongated form opposite to said upward extension, means for bolting the same to the base, said clamping member being imperforated for bolts through the rail ends and having an upper face to seat against the lower face of the head, said socket having an 65 inclined face adjacent to the upper face of the rail flange and said clamping member having an inclined face adjacent to the rail flange on the other side of the rail, and wedges between the rail flange and said inclined faces for clamping the upper faces of the body member and the clamping member up against the under faces of the rail head, said named parts constituting the sole means for connecting the rail ends.

inclined face adjacent to the rail flange on the other side of the rail, and wedges between the rail flange and said inclined faces for clamping the upper faces of the body member and the clamping member up against the under faces of the rail head, said wedges, said body and said clamping member being the sole means for securing the rail ends together, and a compressible mat between the under face of the rail and the upper face of the base and adapted to be compressed by the wedges when the same are tightened up. 5

4. In a rail connector, the combination of an elongated body member having a base to lie upon the cross ties and having an upward extension of 10 elongated form, with a socket to receive the rail flange between the base and said upward extension, said upward extension being imperforated for bolts through the rail ends and having a seat face abutting against the under face of the rail head, a clamping member of elongated form opposite to said upward extension, means for bolting the same to the base, said clamping member being imperforated for bolts through the rail 15 ends and having an upper face to seat against the lower face of the head, said socket having an inclined face adjacent to the upper face of the rail flange and said clamping member having an inclined face adjacent to the rail flange on the other side of the rail, and wedges between 20 the rail flange and said inclined faces for clamping the upper faces of the body member and the clamping member up against the under faces of the rail head, and a compressible mat between the under face of the rail and the upper face of the base and adapted to be compressed by the wedges when the same are tightened up, said wedges tapering in opposite directions so that one wedge is driven in from one end of the body member and the other wedge from the other end, 25 said parts being the sole means for connecting the rail ends. 30

5. In a rail connector, the combination of a body member in the form of a block, having a base to lie upon the cross ties and having an upward extension with a socket to receive the rail flange between the base and said upward extension, said body member having a longitudinal channel in its upper face lying adjacent to the side of the rail head to receive the flange of a 45 wheel rolling on the rails, said upward extension being imperforated for bolts through the rail ends, and having a seat face abutting against the under face of the rail head, a clamping member of elongated block form opposite to said upward extension, means for bolting the same to the base, said clamping member being imperforated for bolts through the rail ends, and having an upper face to seat against the lower face of the head, said socket having an inclined 50 face adjacent to the upper face of the rail flange and said clamping member having an inclined face adjacent to the rail flange on the other side of the rail, and wedges between the rail flange and said inclined faces for clamping the upper faces of the body member and the clamping member up against the under faces of the rail head, said named parts constituting the sole means for connecting the rail ends. 55
